I. L. Davis.

Adjustable Spirit-Level.

No 75534

Patented Mar. 17, 1868

Inventor.

I. L. Davis.

United States Patent Office.

L. L. DAVIS, OF SPRINGFIELD, MASSACHUSETTS.

Letters Patent No. 75,534, dated March 17, 1868.

IMPROVEMENT IN ADJUSTABLE SPIRIT-LEVELS.

The Schedule referred to in these Letters Patent and making part of the same.

TO ALL WHOM IT MAY CONCERN:

Be it known that I, L. L. DAVIS, of Springfield, in the county of Hampden, and Commonwealth of Massachusetts, have invented a new and useful Improvement in Adjustable Spirit-Levels; and I do hereby declare that the following is a full, clear, and exact description thereof, reference being had to the accompanying drawings, making part of this specification, and to the letters of reference marked thereon, in which—

Figure 1 is a plan of a portion of a level with my invention applied.

Figure 2 is a side elevation of the same, with a portion of the level cut away at *k* to more fully show the construction and application of my invention to a level; and

Figure 3 is a plan view of the bubble-glass case, with the bubble-glass inserted.

The nature of my invention consists in the construction and arrangement of a bubble-glass case, whereby the bubble-glass is much more readily and perfectly adjusted with reference to the stock than it is possible to do when constructed in the usual manner, and without any previous adjustment of the bubble-glass to its case when placed therein.

As now and usually constructed, the common spirit-levels of the cheaper quality are adjusted by taking great care when inserting the bubble-glass in its case to so insert it and secure it in place that the said bubble-glass shall be in perfect and proper adjustment with its case. Such adjustment is only performed, attended with much difficulty and trouble, and oftentimes, with the greatest care, the levels, when done, are not in perfect adjustment, as there is no way of changing the adjustment after the gypsum, with which the bubble-glass is secured in place, has set or become hard.

In my invention no care or exactness is required in the insertion of the bubble-glass in its case, as it is unnecessary that the bubble-glass should be in adjustment with its case, as the said bubble-glass is put in adjustment with the stock by means of the bubble-glass case after its insertion in the stock.

That others skilled in the art may be able to make and use my invention, I will proceed to describe its construction and application to use.

In the drawings, A represents the stock of a spirit-level, having a cavity, indicated by the dotted line *c*, fig. 1, made therein, and of about the depth indicated by the line *k k*, fig. 2, and also a still smaller cavity, *c'*, for the reception of the projection *o*. Into this larger cavity *c* is inserted the bubble-glass case *h*, having the bubble-glass *g* previously inserted therein, and properly secured by means of the gypsum, or other proper substance, *l*.

The bubble-glass case *h* is constructed as follows: A metallic box is made of the proper size, having the sides *r r* and ends *r' r'*, and having a bottom, but no cover. To each end of the box or case *h* are attached the ears *b' b'*, said ears being perforated near their outer ends, and a screw-thread cut in said perforation for the reception of the screws *ff*. The upper edges *r r* of the case *h* are made crowning or slightly convex, and a small semicircular space, *s*, is made in each side of the case, so that the bubble may be seen beneath the plate *a*. The ear or projection *o* is firmly attached to the bottom of the case *h*, said projection *o* being perforated at *n*, through which a small pin or pivot is passed, which also passes through the stock A, thus securing the case *h* to the stock A at the point *n*. A small space should be left between the bottom *k* of the cavity *c* and the case *h*, to allow each end of said case *h* a slight vertical play whenever its position shall be changed by turning the screws *ff* either in or out. The plate *a* is then placed above the case *h*, and attached to the stock A by means of the screws *e e e e*, it being better to slightly cut away the upper surface of the stock A and let the plate *a* in, so that the upper surface of the said plate *a* shall be upon the same level with the upper surface of the stock A, and the screws *ff* are inserted in apertures made in the plate *a*, one near each end, and turned or screwed into the threaded apertures in each ear *i* of the case *h*. These ears *i i* being attached to the lower part of each end of the case *h*, and bent upwards, are thus rendered elastic, so that when the bubble-glass is in adjustment with the stock A, and the screws *ff* are turned up firmly, the bubble-glass or its case shall always bear up against the plate *a*, and the case *h* is thus firmly held in place, and prevented from shaking in its socket, and rendering the bubble-glass less liable to breakage.

This arrangement, I claim, has a great advantage over other adjustable levels as now constructed.

The operation of my invention is as follows: If upon trial the bubble-glass shall be found to be out of its proper adjustment with reference to the stock A, one of the screws f is turned farther into one of the ears i. As the head of the screw f comes in contact with the upper surface of the plate a, the ear i, into which the screw f is turned, is drawn upward, and the middle of the case h, swinging upon its pivot n, the other screw f being turned out, its end of the said case h is depressed. In this way either end of the case h may be raised or depressed, until the bubble-case g shall be found to be in proper adjustment with the stock A, or the axis of the bubble-glass g shall be exactly parallel with the bottom of the stock A. Both ears i are prevented from coming in contact with the under surface of the plate a at the same time by the convex form of the upper edges r of the box or case h, and also by the pin n.

Spirit-levels have heretofore been made in which the bubble-glass case was adjustable, but, as said case was not positively and properly secured in its stock after adjustment, they are liable to quickly get out of adjustment again, as, if the stock be turned upside down, the case moves in its socket, and renders the bubble or vial liable to be broken or misplaced in its case; and I am aware that various devices have been used for the purpose of rendering spirit-levels adjustable after their first construction, as in Letters Patent granted to T. N. Hosmer, bearing date November 11, 1862, and numbered 39,906, and others, but said devices differ very materially from mine in construction, arrangement, and operation, and I disclaim any and every part of said devices irrespective of my arrangement and construction; but having described my invention,

What I do claim as new, and desire to secure by Letters Patent, is—

1. The adjustable bubble-glass case h, having the elastic adjusting-ears i and projection o, when constructed and arranged substantially as described and for the purposes herein set forth.
2. I claim, in an adjustable spirit-level, the case h having the elastic adjusting-ears i and the projection o, and operated or adjusted by means of the screws f, in combination with the plate a and pin n, substantially as herein described and set forth.

L. L. DAVIS.
